2,363,304

METHOD OF FORMING AXLE HOUSINGS

William Jack Stephen Ekins, Buchanan, Mich.,
assignor to Clark Equipment Company,
Buchanan, Mich., a corporation of Michigan

Application April 27, 1942, Serial No. 440,726

6 Claims. (Cl. 29—153.1)

This invention relates to a method of forming axle housings, and more particularly is concerned with the formation of an axle housing of the banjo type in which the banjo frame for supporting the differential carrier is offset with respect to the longitudinal center of the housing.

Such housings are employed in connection with trucks and other automotive equipment where more than one driving axle is required, since it is obvious that the drive shaft from the transfer case of the vehicle must be laterally offset to reach the various housings containing the driving axles, and consequently the banjo frame which supports the differential mechanism in the housing must be correspondingly offset.

In the formation of a housing with an offset banjo frame, considerable difficulty has arisen in providing the proper spring pad supports for resiliently supporting the vehicle on the housing. With a normal or conventional type of rear axle housing in which the banjo frame is centered, the spring pads are usually welded or otherwise suitably secured to the oppositely extending arms of the housing, and present no particular difficulty. However, when the banjo portion is offset, the tapered throat which leads from the banjo to the arm of the housing extends through the section where the spring pad must be applied. Several schemes have been developed for applying a spring pad to this throat portion, such as disclosed in the patent to George Spatta, No. 2,273,336, issued February 17, 1942, in which the throat is cut or slotted and the spring pad is then set into position and welded. There are some disadvantages of such a construction, however, in addition to the increased cost of the separate operations of cutting out an arcuate slot and then welding a special type of spring pad in position thereon.

The present invention overcomes these difficulties by providing a novel method of forming such housings, which includes the step of forming a depression in the throat of the housing during the swaging operation in which the throat is straightened and formed to accurate size. This depression is produced by the use of an angularly disposed plunger cooperating with the throat forming machine, and selectively operable to force the metal at that portion of the throat where the spring pad is to be located inwardly to provide a horizontal flattened portion in the throat upon which the spring pad can be mounted while maintaining the other metal in the throat against deformation in any direction.

Preferably, in a preferred form of the inven-

tion a throat forming machine similar to that shown in Spatta Patent No. 1,912,600, issued June 6, 1933, is provided for carrying out the method proposed, which includes the use of a ram to which is detachably secured a mandrel which enters into the banjo portion of the housing and upon opposite movement of the ram, swages the throat into a corresponding female die to move the metal of the throat into proper position for forming a smoothly tapered throat leading from a semi-circular adjacent portion of the cylindrical banjo. In forming the particular axle housing desired in the present invention, the ram is adapted to receive alternately a standard mandrel for that side of the throat which connects to the longer arm of the housing and a special mandrel when the opposite throat is to be formed, which special mandrel is so shaped that after the throat has been swaged into position, 20 the seat forming plunger can operate in conjunction with the mandrel to depress the metal in the throat on the upper side thereof to provide the horizontal seat for the spring pad.

The present invention contemplates, in carrying out the present method, an automatic electrically controlled system controlling the delivery of pressure to various operating cylinders which control the operation of the plunger and the ram. This system is so arranged that upon alternate 30 operations of the ram, the plunger will be actuated whereby the spring pad will be formed in one throat forming operation but not in the other throat forming operation.

With the present method, it is possible to form such throats in the housing with a minimum of time and with no appreciable additional expense of operation. The mechanism is fully automatic in operation, although obviously it could be manually controlled if desired, and constitutes a considerable advance in the art of forming rear axle 40 housings of the offset type.

Other objects and advantages of the present invention will appear more fully from the following detailed description which, taken in conjunction with the accompanying drawings, will disclose to those skilled in the art, the particular construction and operation of a preferred form of the present invention.

In the drawings:

50 Figure 1 is a schematic showing of the pressure and electric control system utilized in performing this operation upon the axle housing;

Figure 2 is an elevational view of the mechanism which is operated to form the spring pad seat in the throat of the banjo;

Figure 3 is a sectional view taken substantially on line 3—3 of Figure 2;

Figure 4 is a sectional view taken substantially on line 4—4 of Figure 2;

Figure 5 is an elevational view of a housing prior to the throat forming operation;

Figure 6 is a plan view of such housing; and

Figure 7 is an elevational view of the housing after the throat forming operations.

Referring now in detail to the drawings, Figure 5 shows an axle housing of the offset type, which has been formed from a piece of flat stock or tubing which has been slotted and had the banjo portion expanded such as by use of the equipment shown in Spatta patents, Nos. 1,925,850, issued September 5, 1933, and 1,926,353, issued September 12, 1933, and 1,958,214, issued May 8, 1934. It will be noted that this axle housing, indicated generally at 5, is provided with a cylindrical banjo portion 6 and with tapering throat portions 7 connecting the banjo to the oppositely extending arms 8. The throat portions 7 of such a housing, due to the banjo forming operation, are provided with humps or irregularities 9 which normally are removed by means of the throat forming equipment shown in Spatta Patent No. 1,912,600 of June 6, 1933.

In forming the throat, there is normally employed a ram, such as indicated at 10 in Figure 1, connected for operation by a piston operating in cylinder 12. At its end the ram is provided with means for locking a mandrel, such as the mandrel 13, thereto. This mandrel operates in a suitable female die block, indicated generally at 14, and having a banjo receiving die portion 15 for receiving the adjacent half of the cylindrical banjo frame, and a throat receiving portion 16 for receiving the throat of the housing. The mandrel 13, when connected to the ram 10, produces a uniformly tapered throat leading from the semi-cylindrical banjo section to the arm of the housing. For purposes of the present invention, however, there is provided a second mandrel 17 which, as shown in detail in Figure 2, is provided with a flattened portion 18 and a rather abruptly rising surface 19 which then merges into the generally arcuate shape of the cylindrical banjo frame. The die block 14 in this form of the invention is provided with an offset extension 20 carrying a suitable frame 22 upon which is supported the cylinder 23 which operates the spring pad seat forming plunger. The cylinder 23 carries a suitable piston having the extension 24 projecting into the frame 22, and provided with a cross head 25 operating in the web or partition 26 of the frame supporting the piston against lateral flexing. At the end of the cross head 25 there is provided the ring 26 connected to the connecting point of the links 27 and 28 which provide a toggle joint, the opposite end of the link 27 being connected to the plunger 29 reciprocatory within a suitable recess in the extension 20. The link 28 at its opposite end is fulcrumed on the pin 30 supported on the bracket 32 secured by means of the nut 33 to the frame 22. The bracket 32 is adjustable in position by means of the adjusting screws 34. A suitable stop screw 35 is provided carried by the end wall 36 of the frame for preventing the toggle joint pin 37 from passing over center.

In Figure 2 the mechanism is shown in its fully operated position with the plunger 29 fully projected into the recess 38 in the extension 20, and thereby pressing against the outer surface of the housing wall 39 to press it into position

against the mandrel 17, thereby forming the spring seat portion 40 shown in Figure 7. At its lower end the plunger 29 is provided with a die member 42 which is shaped to provide the desired cooperation with the mandrel 17 for producing the flattened spring seat. The lower end of this die member 42 is indicated at 43 in Figure 3, and when the plunger is retracted in position by the piston rod 24 moving the toggle joint away from the stop 35, the lower end 43 of the die 42 is moved upwardly an amount sufficient to clear the transverse channel 44 formed in the die block 14. This allows the auxiliary die member 45 to be moved laterally into position over the opening 46 in which the mandrel 17 is disposed, the auxiliary die 46 having the arcuate shaped die surface 47 which cooperates with the standard mandrel 13 to form a full throat on the opposite side of the housing. The movement of the auxiliary die 45 laterally is controlled by a rod 48 operating within a pressure cylinder 49 secured by means of the bracket 50 to the side of the die block 14. The cylinder 49 is also alternately controlled so that as the plunger 29 is retracted in position and the opposite end of the housing inserted in the die block 14, the auxiliary die 45 will be moved into position to provide the standard throat shape.

In Figure 4 there is disclosed the details of the cross head construction for the piston rod 25 which operates the spring seat forming the plunger 29. The partition wall 26 of the frame 22 is provided with the transverse substantially cylindrical opening 50, and the cross head 25 connecting the piston rod 24 to the link 26 is provided with arcuate shoes 52 forming suitable slides for guiding the cross head in the intermediate partition 26.

It will be noted that the auxiliary frame carrying the plunger operating mechanism and indicated at 22 is supported on the die block 14 by means of inturned flange portions 53 carried at the lower end of the frame and sliding in suitable ways 54, whereby the frame can be adjusted longitudinally with respect to the die block 14. Suitable locking screws 55 serve to lock the frame in desired position.

Considering now Figure 1 of the drawings which discloses a schematic pressure and electrical control system for the automatic operation of this mechanism, there is provided a spool 60 having arms 62, 63 and 64 thereon adapted to be engaged by the actuating bar 65 carried by the ram or plunger 10 controlled through cylinder 12. The cylinders 12 and 23 have pressure supplied thereto from an oil pump indicated at 66, which has its pressure side 67 connected through conduits 68 and 69 to suitable solenoid control valves 70 and 72, respectively. The solenoid control valve 70 has outlet conduits 72 and 73 leading to opposite ends of the cylinders 23 for effecting selected reciprocation of piston rod 24. The valve 72 has conduits 74 and 75 connected to opposite ends of the cylinder 12 for selectively reciprocating the ram or plunger 10. The return lines from the valves 70 and 72 to the pump are indicated by the dotted line conduit 76.

In the operation of this mechanism, the mandrel 13 is first placed upon the end of the ram 10, and the housing is placed in position for a standard throating operation in the die block 14. The main starting switch 77 is then actuated which actuates the valve 72 to admit fluid under pressure from conduit 69 through conduit 74 to the forward end of cylinder 12, thereby retracting

the ram 10 and forcing the mandrel 13 into the throat of the housing to perform the standard throat forming operation. At this time, the cylinder 49, which is supplied with pressure from a control valve 78 receiving pressure from the supply conduit 79 has the switch 80 of the electrically controlled actuator for the valve 78 closed, whereby the valve is open to allow pressure from the supply line 79 to pass through the valve and conduit 82 to the right hand side of cylinder 49, as viewed in Figure 1, whereby the profile die 45 carried by the piston arm 48 is moved into position within the die block 14 in the transverse channel 44. At this time, the plunger 29 is in retracted position. As a result, when the mandrel 17 is forced into the throat of the housing, a uniform symmetrical throat is formed in this end of the banjo.

When this throating operation is finished, the stop button of the starting switch 77 is actuated, which in turn controls the valve 72 to admit pressure from conduit 69 through conduit 75 to cylinder 12, thereby releasing the ram 10 for movement to unloading position. At the same time, as the ram 10 moves to the left, the arm 65 thereof rotates the spool 60, but since the arm 63 is shorter than either arm 62 or 64, the switch 80 remains closed, and consequently the profile die 45 remains in position. The housing is then reversed with the short end placed in the die block and with the same mandrel 13 on the ram 10. The starting switch at 77 is re-engaged, whereby the same cycle of operation is reproduced in the opposite throat of the housing, thereby providing a smooth throat in more or less conventional manner for both throats of the housing. Upon pressing the stop button of the switch 77, the ram moves to the left to unloading position, and in this case the arm 62 is rotated into position, closing switch 83, while arm 64 opens switch 80. As a result of this operation, the cylinder 49 receives pressure from control valve 78 through conduit 82, withdrawing the profile die 45 from the recess 44, and thereby clearing the way for operation of plunger 29. When the profile die 45 moves outwardly of the recess 44, the bracket 85 carried at the end of this die operates to close a circuit from the pressure switch 86 in conduit line 74 through the conductor 87 and switch 88, thereby establishing a circuit through conductor 89 to the solenoid control 90 at the left hand side of control valve 70. This circuit is not completed but is merely conditioned for operation, and completion of the circuit is dependent upon operation of the pressure switch 86. The mandrel 17 is then placed upon the ram 10 and the start switch at 77 is again engaged.

This results in the ram being drawn through the housing arm moving the mandrel 17 into position in the throat of the housing. As the mandrel moves into position, the pressure in conduit 74 increases to a point where pressure switch 86 closes, thereby establishing a circuit to the solenoid actuator 90. This in turn opens the valve 70 to allow fluid under pressure to flow from conduit 68 through conduit 72 to the outer end of cylinder 23. This forces the piston rod 24 outwardly of the cylinder straightening the toggle joint formed by links 27 and 28, and thereby forcing the plunger 29 downwardly through the recess 38 so that the die head 42 at the lower end of the plunger engages the outer wall of the housing throat and depresses the same to the position shown in Figure 2. When the toggle 75

joint has reached limiting position as provided by the stop screw 35, the pressure in conduit 72 builds up to a point to which it operates the pressure switch 91, closing the circuit from conductor 92 to conductor 93, thereby energizing the solenoid actuator 94 at the opposite side of the valve 70. This in turn allows the pressure in the left hand end of cylinder 23 to be exhausted through conduit 72 and return line 76 while pressure builds up in the opposite end of the cylinder through conduit 73, thereby retracting plunger 29 outwardly through recess 38. The stop switch is then energized at 77, unloading the ram and mandrel 17, and the housing is then removed from the die block. This produces a housing of the form shown in Figure 7 having a depressed horizontal portion 40 formed by the plunger 29, which in turn receives a spring pad secured on the surface thereof at the proper location with respect to the spring pad at the opposite end of the housing to provide the desired spring spacing beneath the vehicle.

It is not believed necessary to go into all the details of the construction and operation of the various valves and control mechanisms associated with the present invention, as they form no part of the method of forming such housings by the present invention. Suffice it to say that with this type of control system, the housing has its throat swaged to proper shape, and the spring pad seat formed therein automatically.

It is to be understood that other means and methods of control might be employed without in any way departing from the scope and spirit of the present invention, and I therefore do not intend to be limited except as defined by the scope and spirit of the appended claims.

I claim:

1. In the method of forming a rear axle housing of the offset banjo type, which includes forming a cylindrical banjo section having oppositely extending arms of unequal length, inserting a mandrel in the throat between said banjo section and each arm to form smoothly tapering throat portions by drawing said mandrel and housing into a die, and inserting a second mandrel having a relieved portion into one of said throat portions and forcing said mandrel and housing again into said die, the novel step of forming a horizontal spring pad seat which comprises forcing metal in said throat surface adjacent said relieved portion radially and angularly inwardly against said relieved portion while maintaining all other portions of throat metal against deformation in any direction.

2. In the method of forming a rear axle housing of the banjo type having smoothly tapering throat portions between the cylindrical banjo section and the oppositely extending arms, the step of forming a spring pad seat in one of said throat portions which comprises maintaining said throat portion against deformation in any direction except at the portion where said seat is to be formed, and forcing the metal at said last-named portion inwardly against a recessed abutment to produce a horizontal spring pad seat located radially beyond the diameter of the adjacent arm.

3. In the method of forming a spring pad seat in the throat portion of a banjo type axle housing, which includes drawing said throat portion with a male mandrel therein into a female die having a laterally shiftable section, the novel steps comprising internally supporting the throat metal against inward deformation except in the portion

where said spring pad seat is to be formed, externally supporting the throat metal against deformation, withdrawing a portion of external support in the portion where said spring pad seat is to be formed, and then forcing throat metal inwardly at said last-named portion to form a horizontal spring pad intermediate the ends of the throat portion.

4. In the method of making an axle housing having an offset expanded cylindrical banjo portion, the novel steps which comprise first forming a smoothly tapered throat portion between said banjo portion and the adjacent housing arm by inserting a mandrel in said throat portion and moving the mandrel and housing throat into a female die, then reforming a portion of said throat portion to form a spring pad seat by retaining all other portions thereof against deformation and forcing metal in said one portion inwardly and laterally to produce a flattened horizontally extending step in the intermediate surface of said throat portion.

5. In the method of making an axle housing having an expanded cylindrical banjo portion and oppositely extending arms of unequal length, the portions of said housing between said banjo and said arms comprising smoothly tapering throats merging from the diameter of said banjo to the cross-section of said arms, the novel step of forming a spring pad in the throat between the

shorter of said arms and said banjo, which comprises internally supporting the metal in said throat except for a relieved portion where said seat is to be formed, externally confining said 5 throat metal, and deforming inwardly a portion of said confined metal into said relieved portion to flatten the deformed metal into a horizontal spring pad seat lying in a plane substantially parallel to the longitudinal axis of said housing.

10 6. In an axle housing of the type having a transverse cylindrical banjo joined to oppositely extending arms by smooth tapering throats of generally frusto-conical form, the method of forming a spring pad seat in one of said throats intermediate the ends thereof which comprises internally supporting the metal in all portions of said throat against inward movement at the portion where said seat is to be formed, externally supporting the metal of said throat against deformation outwardly, deforming the throat metal inwardly at said one portion where said seat is 15 to be formed, and providing within said throat a horizontal internal abutment limiting inward movement of said deformed metal to produce a horizontal spring pad seat spaced radially from the longitudinal axis of said housing a distance intermediate the radial extents of the large and small ends of said throat.

20 25 WILLIAM JACK STEPHEN EKINS.
